Primary Examiner—Mimosa De(74) Attorney, Agent, or Firm—Hoffmann & Baron, LLP(57) CLAIM

The ornamental design of a wardrobe, as shown and described.

DESCRIPTION

FIG. 1 is a perspective view of the wardrobe according to my claimed design; the door pulls and drawer pulls are not part of the claimed design and are shown in phantom;

FIG. 2 is a top plan view thereof;

FIG. 3 is a front elevation view thereof;

FIG. 4 is a right side elevation view thereof; and,

FIG. 5 is a left side elevation view thereof.

The back and underside of the wardrobe are not part of the claimed design and are not shown.
